(57) **CLAIM**

The ornamental design for a replaceable ground ring and master ring, substantially as shown and described.

DESCRIPTION

FIG. 1 is a top-front isometric view of a replaceable ground ring and master ring according to a first embodiment;

FIG. 2 is a top-rear isometric view of the replaceable ground ring and master ring of FIG. 1;

FIG. 3 is a front view of the replaceable ground ring and master ring of FIG. 1;

FIG. 4 is a rear view of the replaceable ground ring and master ring of FIG. 1;

FIG. 5 is a top view of the replaceable ground ring and master ring of FIG. 1;

FIG. 6 is a bottom view of the replaceable ground ring and master ring of FIG. 1;

FIG. 7 is a left-side view of the replaceable ground ring and master ring of FIG. 1;

FIG. 8 is a right-side view of the replaceable ground ring and master ring of FIG. 1;

FIG. 9 is a top-front isometric view of a replaceable ground ring and master ring according to a second embodiment;

FIG. 10 is a top-rear isometric view of the replaceable ground ring and master ring of FIG. 9;

FIG. 11 is a front view of the replaceable ground ring and master ring of FIG. 9;

FIG. 12 is a rear view of the replaceable ground ring and master ring of FIG. 9;

FIG. 13 is a top view of the replaceable ground ring and master ring of FIG. 9;

FIG. 14 is a bottom view of the replaceable ground ring and master ring of FIG. 9;

FIG. 15 is a left-side view of the replaceable ground ring and master ring of FIG. 9; and,

FIG. 16 is a right-side view of the replaceable ground ring and master ring of FIG. 9.

Portions of the article shown in dotted lines forms no part of the claimed design.
